UNITED STATES PATENT OFFICE.

MAX HAEBERLEIN, OF NEW YORK, N. Y., ASSIGNOR OF ONE-HALF TO THE PELTON WATER WHEEL CO., OF SAN FRANCISCO, CALIFORNIA, A CORPORATION OF CALIFORNIA.

FLY-BALL GOVERNOR.

941,775.

Specification of Letters Patent. Patented Nov. 30, 1909.

Application filed February 1, 1909. Serial No. 475,386.

To all whom it may concern:

Be it known that I, MAX HAEBERLEIN, a citizen of the Empire of Germany, residing in New York, in the borough of Manhattan, county and State of New York, have invented certain new and useful Improvements in Fly-Ball Governors, of which the following is a specification.

This invention relates to a fly-ball governor which combines extreme sensitiveness with a simple and durable construction; and the invention consists of an inclosed fly-ball governor in which the fly-ball levers are mounted on knife-edges and are acted upon directly by adjustable counterbalancing-springs in such a way that there is no friction between the springs and the levers, the levers being linked, independently of the springs, to a vertically slideable sleeve which is connected to the regulating mechanism.

In the accompanying drawings, Figure 1 represents a vertical central section of my improved fly-ball governor, Fig. 2 is a vertical section taken on a plane at right angles 25 to the sectional plane of Fig. 1, and Fig. 3 is a horizontal section on line 3, 3, Fig. 2.

Similar letters of reference indicate corresponding parts throughout the different figures.

Referring to the drawings, *f* represents the spindle of my improved fly-ball governor, which is geared to a prime motor of any kind and which follows the speed-changes of the same. The spindle *f* is provided with a central bore *f*¹ at its upper end and with slots *b* at opposite sides of the bored out portion. To the bored out upper end of the spindle *f* is applied the conically-flaring bottom-plate *c*¹ of a cylindrical casing or shell *c*, which bottom-plate is provided with a central hub *c*² adapted to be screwed or otherwise attached to the spindle, and with a circumferential rim *c*² to which the rimmed lower end of the body or main portion *c*³ of the casing or shell *c* is attached by means of fastening screws *c*⁴. The top of the casing or shell is made conically flaring, like the bottom-plate, and also provided with a central hub *c*⁵ into which is screwed the threaded pin *d* for maintaining in position a cap-plate *e*, which can be adjusted higher or lower by means of the threaded pin, which latter is provided with a square or other head at its outer end for facilitating the ad-

justment of the cap-plate by means of a wrench.

At the interior of the shell, and at diametrically-opposite points of the same, are arranged two knife-edged fulcra *g*, which are attached by means of fastening screws *g*¹ to the inner circumference of the bottom-plate of the casing or shell *c*, and which engage the recessed apexes of two angular fly-ball levers *h*, which are provided with fly-balls of the usual size at their upper ends and which are pivoted at the inner ends of their lower arms to the upper ends of links *a*, *a*. The links *a*, *a* are arranged beside each other and extended into the bored end of the spindle *f*, their lower ends being connected by a transverse pin *b*¹ with a sleeve *b*² which is provided with an exterior grooved collar *b*³ in which a ring *r* is placed that is connected with the regulating train. The pivot-pin *b*¹ is connected with the upper part of the sleeve, as shown clearly in Fig. 2. Between the lower arms of the fly-ball levers *h* and the cap-plate *c* are interposed helical springs *s* for counterbalancing the centrifugal force exerted on the fly-ball weights. It will be readily seen that the centrifugal force of the fly-ball weights is counterbalanced directly by the springs *s*, without being transmitted to the pivot-pins of the links *a*, *a*. The resultant of the centrifugal force and the pressure of the springs passes to the fulcra *g*, *g* without creating any appreciable friction between the levers and the fulcra. This arrangement insures a very sensitive and effective governor. The knife-edged fulcra are preferably made of steel so as to stand the wear to which they are exposed by the oscillations of the fly-ball levers. The casing or shell, and the fly-ball levers rotate together, and the speed of the motor is regulated through suitable mechanism actuated by the movement of the fly-ball levers as they assume the position resulting from the centrifugal force and the force of the springs on the fly-ball levers.

Having thus described my invention, I claim as new and desire to secure by Letters Patent:

1. A fly-ball governor comprising a rotatable spindle, a sleeve sliding on the same, fly-ball levers provided with weights at their upper ends, a casing or shell inclosing the fly-ball levers, fulcra at diametrically-oppo-

site points on the base of said casing or shell, a cap-plate supported in the upper part of the casing, separate counter-balancing springs interposed between the lower 5 arms of the fly-ball levers and the cap-plate, and means connecting the fly-ball levers with the movable sleeve on the spindle.

2. A fly-ball governor comprising a rotatable spindle having a bored out upper 10 end, a sleeve sliding on said spindle, a casing or shell attached to the spindle, fulcra at diametrically opposite points on the base of said casing or shell, fly-ball levers swinging on said fulcra and rotating with the spindle 15 and shell, a cap-plate supported in the upper part of said casing or shell, separate counter-balancing springs interposed between the lower arms of the fly-ball levers and the cap-plate and pivot-links extending into the 20 bored out end of the spindle and connecting the lower arms of the fly-ball levers with the movable sleeve on the spindle.

3. A fly-ball governor comprising a rotatable spindle carrying a casing, a sleeve 25 movable on the spindle, oppositely disposed fulcra in said casing, angular fly-ball levers swinging on said fulcra, a cap-plate supported in the upper part of the casing, separate counterbalancing-springs interposed 30 between the cap-plate and the inner ends of the fly-ball levers, and means connecting the fly-ball levers with the sleeve movable on the spindle.

4. A fly-ball governor comprising a rotatable spindle, a sleeve slidably thereon, angular fly-ball levers having weights at their 35 upper ends and circular recesses on the upper face of their inner ends, a casing supported on said spindle and carrying fulcra on which 40 the fly-ball levers are pivoted, a cap-plate supported in the upper part of said casing and having circular recesses in its lower face, counterbalancing-springs interposed between the recesses of the cap-plate and the recesses

of the fly-ball levers, and means for connecting the fly-ball levers with the movable sleeve on the spindle.

5. A fly-ball governor comprising a rotatable spindle, a sleeve slidable on the spindle, angular fly-ball levers provided with weights at their upper ends and with circular recesses at their inner ends, a casing or shell inclosing the fly-ball levers and secured to the rotatable spindle, a fulcra at oppositely disposed points on the base of the 5 casing, a cap-plate supported in the upper part of the casing and having a pair of circular recesses in the lower face thereof, counterbalancing-springs interposed between said levers and said cap-plate with their 60 ends seated in the circular recesses of the same, and means connecting the fly-ball levers with the sleeve movable on the spindle.

6. A fly-ball governor comprising a rotatable spindle having a bored out upper 65 end, a sleeve slidable on the spindle, a casing attached to the spindle, fulcra at opposite points on the base of the casing, angular fly-ball levers swinging on said fulcra and having weighted upper ends and circular recesses on the upper faces of their inner ends, a cap-plate carried in the upper part of the 70 casing and having a pair of circular recesses in its lower face, counterbalancing-springs interposed between the recesses of the cap-plate and the recesses of the fly-ball levers, and pivot-links extending into the bored out 75 end of the spindle and connecting the inner ends of the fly-ball levers with the sleeve movable on the spindle.

In testimony that I claim the foregoing as my invention, I have signed my name in presence of two subscribing witnesses.

MAX HAEBERLEIN.
